UNITED STATES PATENT OFFICE.

JOHN FRANCIS GOODWIN, OF SARNIA, ONTARIO, CANADA.

WATER-HEATER USING A FLUID FUEL.

1,382,283.

Specification of Letters Patent. Patented June 21, 1921.

Application filed October 13, 1919. Serial No. 330,244.

To all whom it may concern:

Be it known that I, JOHN F. GOODWIN, of the city of Sarnia, in the county of Lambton, Province of Ontario, Canada, have invented 5 certain new and useful Improvements in Water-Heaters Using a Fluid Fuel, of which the following is a specification.

This invention relates to that type of water heater in which the heated products 10 of combustion from a fluid burner located at the bottom of a casing are led around or through a series of connected water sections through which the water circulates, and my object is to devise a heater of this 15 type which, while cheap to construct, is much lighter in weight and quicker in heating than ordinary heaters using cast iron sections.

I attain my object by means of the 20 constructions hereinafter described and illustrated in the accompanying drawings in which—

Figure 1 is a side elevation of a heater constructed in accordance with my invention 25 with the door open, and partly broken away;

Fig. 2 a plan view of one-half of one of the sections on an enlarged scale;

Fig. 3 a cross section of one of the sections on the line *a—a* in Fig. 2; and

30 Fig. 4 a perspective view of one of the partitions forming the waterways in a section.

In the drawings like numerals of reference indicate corresponding parts in the different figures.

1 is a casing, which is provided with a 35 door 2, preferably of substantially half the circumference of the casing. The top of the casing is provided with the cover 3, through 40 which is formed the opening to the vent pipe, which opening is surrounded by a collar 4. An opening for the passage of the outlet water pipe 5 is also formed in the cover.

45 In the fixed half of the casing near the bottom is located the burner 7, which is supported on ribs 6 formed on the casing. 8 are the water sections. These are all of the same construction, size and shape, and are 50 connected in series. The inlet water pipe 9 communicates with the bottom section and the outlet water pipe 5 with the top section.

Each water section in plan is shaped as the segment of a circle, having the same 55 radius as the interior of the casing, the segment being greater than a semi-circle.

A water connection 10 is secured in an opening in one side of the section at the center of a circle of which the curved edge of the section is an arc. A second water connection 11 communicates with an opening in the other side close to the curved edge and substantially at the same distance from the straight edge of the section as the first mentioned opening. These water connections are connected by nipples 12 so that each section is connected by its central connection with the adjacent section at one side and by its peripheral connection with the water section at the other side.

Each section is also provided with partitions forming a tortuous water channel through the section which will cause the water flowing through the section to circulate over substantially all the heating surface of the same. In the preferred arrangement I employ two partitions 13 and 14. The partition 13 starts from the straight edge of the section adjacent the outer opening and extend substantially concentric with the curved side to a point adjacent to but spaced from the straight edge at the other side, while the second partition, substantially concentric with the first, starts from the straight edge at the opposite side 80 of the central opening and extends about said central opening to a point adjacent to, but spaced from the straight edge. These partitions are so spaced and proportioned as to provide a continuous water way of approximately the same cross sectional area at 90 all points in its length. The flow of water through the section is thus continuous and easy without any sudden contractions and expansions to cause local variations in the 95 rate of flow and the consequent loss of circulating power.

As my object is to make the heater as light as possible and adapted for quick heating, I have devised a construction by means of 100 which the sections may be made of sheet metal stampings. Each section as shown is formed of six parts welded together. These parts are the two stamped plates 15 having turned down edges 16, the two partitions 105 13 and 14, and the water connections 10 and 11. The partitions 13 and 14 are each provided with lugs 17 adapted to enter similarly shaped slots formed in the plates 15. The water connections 10 and 11 are preferably rabbeted so as to fit into the openings 110 in the plates, while the shoulders formed by

rabbeting rest on the outer surfaces of the plates. The parts described are readily assembled and the meeting edges of the plates welded electrically or by oxy-acetylene flame, also the lugs 17 in their slots and the water connections 10 and 11 in their opening.

5 What I claim as my invention is:—

- 10 1. A sheet metal water section for a water heater shaped in plan as the segment of a circle greater than a semi-circle and formed of two horizontal parts welded together and provided with a water connection opening in one side at the center of the circle of which the curved edge of the section is an arc, and a second water connection opening in the other side close to the curved edge and also to the straight edge of the section, a sheet metal partition starting 15 from the straight edge of the section adjacent the outer opening and extending substantially concentric with the curved side to a point adjacent to but spaced from the said straight edge, a second partition 20 substantially concentric with the first starting from the straight edge at the opposite

side of the central opening from the starting point of the first partition and extending about said central opening to a point adjacent to, but spaced from the straight 30 edge, the partitions being spaced and proportioned to provide a continuous waterway of approximately the same cross sectional area at all points in its length and being welded in place.

35

2. A water heater comprising a plurality of water sections constructed as set forth in claim 1 suitably spaced and connected; and a casing in which said sections are contained, said sections being set with their 40 curved edges substantially touching the casing, but in different positions so that products of combustion passing through the casing are caused to follow a tortuous course about the sections on their way from the 45 burner to the upper end of the casing.

Signed at the city of Sarnia this first day of October, 1919.

JOHN FRANCIS GOODWIN.
